UNITED STATES PATENT OFFICE.

ROBERT T. JOHNSTON, OF PLAINFIELD, NEW JERSEY, ASSIGNOR TO THE CAMPBELL PRINTING PRESS & MANUFACTURING COMPANY, OF NEW YORK, N. Y., A CORPORATION OF NEW YORK.

ROTARY SWITCH.

SPECIFICATION forming part of Letters Patent No. 761,769, dated June 7, 1904.

Application filed March 4, 1898. Renewed October 3, 1903. Serial No. 175,697. (No model.)

To all whom it may concern:

Be it known that I, ROBERT T. JOHNSTON, a citizen of the United States, residing at Plainfield, in the county of Union and State of New Jersey, have invented a new and useful Rotary Switch, of which the following is a specification.

The aim of this invention is to improve the parts and arrangements of parts used in sheet-associating devices, and especially the switching devices used in such mechanism.

I have shown in the accompanying three sheets of drawings and will hereinafter describe one application of my improved switching mechanism.

Referring to said drawings, Figure 1 is a side elevation of a sheet-delivery mechanism in which my invention is used. Fig. 2 is a sectional elevation taken just inside of one of the frames. Fig. 3 is a detail showing the switch. Fig. 4 is an end elevation of part of the mechanism; and Figs. 5, 6, and 7 are diagrammatic views illustrating the action of my improved switch.

I will now describe the delivery mechanism shown in the drawings and in such description will be contained a description of my improved switch.

The operative parts hereinafter described may be mounted in any suitable framing, as A.

F represents a former over which a web or webs may be folded.

10 and 11 are the ordinary rolls used at the nose of the former, and 12 and 13 are the drawing rolls or cylinders, which act to draw the web or webs over the former. From between the rolls 12 and 13 the folded web or webs is or are led by means of tapes *a* to the cutting-cylinders 14 and 15, the tapes *a* turning down over the tape-roll 17 and the web or webs being guided to the cutting mechanism by means of suitable guide-fingers 160. These cutting-cylinders 14 and 15 are preferably arranged to cleanly sever the web into sheets. From these cutting-cylinders the sheets will pass down between the tapes *b* and the guides 18 to a collecting-cylinder 20. The

tapes *b* are led around the tape-rolls 16, 25, and 26, as shown, so as to embrace a portion of the periphery of the collecting-cylinder 20. 50 Also bearing on the surface of the collecting-cylinder 20 are the tapes *c*, which are led around the tape-rolls 21 and 22, as shown.

Guides 24 are arranged as shown, and the ends 240 of the guides form the entrance or 55 meeting point of two pathways, one pathway being up around the collecting-cylinder 20 between the same and the tapes *c* and the guiding ends 180 of the guides 18, again between the collecting-cylinder 20 and the tapes *b*, and 60 the other pathway being away from the collecting-cylinder 20 between the said guides 24 and the tapes *b*. The sheets from the collecting-cylinder will normally pass into the pathway between the tapes *b* and the guides 65 24, and to control the entrance of the sheets into the other pathway I use my improved switching mechanism, which I will hereinafter term the "rotary" switching mechanism S. The sheets, collected or otherwise, as they 70 pass from the collecting-cylinder will run out on the tapes *b*, down over guides 260, against a suitable stop 27. The tapes *a* are turned over the tape-rolls 23° to assist in carrying the sheets down on these guides 260. When the 75 sheets reach the stop 27, a rotary tucker or folder T of the usual pattern will tuck or fold the sheets between the folding-rollers 28 and 29, and from these rollers the folded sheets will be led, by means of the tapes *a* and *d*, to 80 the delivery mechanism. The tapes *a* are turned up over the folding-roller 28. From the folding-rollers 28 and 29 the tapes *a* and *d* are led over the guiding rolls or cylinders 30 and 31 to the cylinder or turning-roll 32. 85 From the cylinder 32 the tapes *a* are led, by means of tape-rollers 33, 34, and 35, back to position under the drawing-cylinders 12 and 13. The tapes *d* pass onward from this cylinder or roll 32 and are led by means of tape-rolls 37 and 36 back to the folding-roller 29. 90 As the folded sheets shoot from between the cylinders or rolls 32 and 33, they will run under stationary guides 38 and will be

stripped from the tapes by means of fly-fingers 39, mounted on the shaft 40, which shaft 40 is oscillated by means of a pitman 41, connected to a wrist-pin carried by the shaft of the cylinder 32, which pitman connects by crank 42 to said shaft 40. This mechanism will deliver the sheets onto the delivery-tapes 43, which are led around the rollers 44, 45, and 46, as shown, and these delivery-tapes are 10 jogged or slowly moved by any of the usual mechanisms for this purpose to slowly deliver the folded products.

It will be seen that the fixed guides 38 and the tapes 43 form a wedging-pathway into 15 the apex of which the head of the rapidly-moving folded sheet is run. This will nicely and easily arrest the movement of the sheet, and just as this action takes place the fly-fingers 39 will knock the sheet down clear of the 20 tapes *d* and the fixed guides 38.

The rotary switch, which is the especial feature of my invention, consists of a shaft 50, mounted in suitable brackets in the framing A, and on this shaft 50 are mounted arms 25 51, which arms are counterweighted, as at 52. A shaft 54 is arranged between these arms, as shown, and mounted on this shaft are a number of curved guide or switch fingers 55, which will intermesh with the projecting ends 30 240 of the guides 24. This shaft 54 has on the end thereof a crank or bracket 56, and a screw 57 is passed through the same and tapped into one of the arms 51, whereby by removing the screw and turning the arm the 35 switch-fingers can be turned down toward the shaft 50 into an inoperative position, as shown in Fig. 3. The action of this rotary switch mechanism is as follows: By the gearing hereinafter described the rotary switch 40 will make one turn for every two turns of the collecting-cylinder 20. It will be seen that from the point of the guide-fingers 24, as before specified, there is provided a long and short pathway for the sheets—that is, the long 45 pathway will include a travel around the collecting-cylinder. It also will be seen that the sheets will normally pass from the collecting-cylinder out on the tapes *b*; but every alternate sheet will be taken by the fingers 55 of the 50 rotary switch and the leading edge thereof lifted to come into the bite of the tapes C upon the collecting-cylinder 20. This will cause every alternate sheet to pass around the collecting-cylinder and to associate with the next 55 succeeding sheet. This action is shown clearly in the diagrammatic figures on the third sheet of the drawings. This switching mechanism is a very desirable mechanism for this purpose. The ordinary switch used for this 60 purpose is cam-actuated and will rapidly and quickly wear itself out, while, on the other hand, a mechanism which continually rotates has no jars or shock imparted thereto and

does not depend on the accuracy of a cam or cams for its nicely of operation. Further, a 65 part which is rotary in action as compared with a part which oscillates or reciprocates has great speed, and speed is the desired object of all sheet-delivery mechanisms. It will be seen that the switch-fingers 55 when adjusted to their operative position are rigidly connected to the shaft 50 or to the axle of the switch and that their action is dependent merely and only upon the rotation thereof, whereby cams, eccentrics, and other devices 70 to operate said fingers are dispensed with. This construction provides a device which is very easy of manufacture, simple in its parts, of long life, and accurate in operation.

In the especial organization shown the cutting-cylinders will cut the sheets cleanly from the web, and these sheets will be associated as before described. This can be done without the use of accelerating-tapes, grippers, or pins and without tearing or leaving teats on 85 the sheets, thus producing a very high-grade product.

By rendering the rotary switch inoperative, as before described, sheets can pass from the cutting-cylinders directly to the rotary folder, 90 and thus either a single or associated product can be delivered. The rotary switch can also be rendered inoperative by disconnecting the gear on the shaft thereof from connection to said shaft by any of the usual key 95 or clutch mechanisms, so that the rotary switch will not turn as the remaining parts of the mechanism are operated. When this arrangement is used, the switch-fingers are left in a position clear of the collecting-cylinder 100 when not in use. Although I have shown this rotary switch as used in connection with a collecting-cylinder, it is obvious, of course, that the same may be used to direct sheets into different pathways even if such pathways 105 do not comprehend a collecting-cylinder.

The gearing for driving the parts may be of any of the ordinary forms, and the way I arrange the same in the device shown in the drawings is as follows: 501 designates a power-shaft which carries a pinion 502, which meshes with a gear 500 on the shaft 50 of the rotary switch. The gear 500 meshes with a gear 200 on the collecting-cylinder, and the proportion in this particular device is two to one, so as 110 to get the operation before described. The gear 200, by means of a suitable intermediate 201, drives the gears 150 and 140 of the cutting-cylinders. The drawing-cylinders 12 and 13 are driven from the gear 140 by means of intermediate 142 and gears 120 and 130. By means of gears 350, 351, and 320 the turning cylinder 32 may be driven from the gear 120. By means of gears 503 and 504 the rotary tucker is driven. By means of further gearing, as shown, which is not necessary to de- 115 120 125

scribe, the various other rolls and parts of the mechanism may be driven. Any other gearing may be used for this purpose.

5 A plurality of rotary switches may be mounted on the same axle, if desired, and by properly proportioning the gearing different numbers of sheets may be collected.

10 The details of the rotary folder or tucker may be of the ordinary construction—that is, the same consist of two rotating arms which carry a shaft on which the tucker-blade t^2 is mounted, and on this shaft is arranged a small pinion t , which engages with an internal gear t' , so that the tucker-blade will act in the ordinary manner to tuck or fold the sheets into the bite of the folding-rolls 28 and 29.

15 The details and arrangements herein described may be greatly varied by a skilled mechanic without departing from the scope 20 of my invention as expressed in the claims.

Having thus fully described my invention, what I claim, and desire to secure by Letters Patent, is—

25 1. The combination of two pathways and a continuously-rotating switch rigidly connected to its axle for controlling the entrance of sheets into said pathways.

30 2. The combination of a long and a short pathway, and a continuously-rotating switch rigidly connected to its axle for controlling the entrance of sheets into said pathways.

35 3. The combination of a pathway in which sheets normally pass, a second pathway, and a continuously-rotating switch rigidly connected to its axle for deflecting sheets into said second pathway.

40 4. The combination of a collecting-cylinder and a continuously-rotating switch rigidly connected to its axle for directing sheets around said collecting-cylinder.

45 5. The combination of a collecting-cylinder, a continuously-rotating switch for directing sheets around said collecting-cylinder, and gearing between these two parts, arranged so that the collecting-cylinder will make two turns for every turn of the switch, whereby each alternate sheet will be associated with its following sheet.

50 6. The combination with a pair of cutting-cylinders, a collecting-cylinder, means for leading the sheets from the cutting-cylinders to the collecting-cylinder, and a continuously-rotating switch rigidly connected to its axle coöperating with the collecting-cylinder.

55 7. The combination of two pathways for sheets, and a continuously-rotating switch, consisting of two arms mounted on a shaft, a shaft extending between the two arms, a number of guiding-fingers rigidly mounted on said

shaft, and means for locking said shaft in position to bring said guiding-fingers into operation.

60 8. The combination of two pathways and a continuously-rotating switch comprising a shaft, two arms arranged on said shaft, a shaft 65 journaled in said arms, a number of switch-fingers mounted on said shaft and means for turning and securing said shaft so as to hold the switch-fingers in operative or inoperative position as desired.

70 9. The combination of a collecting-cylinder, guide-fingers arranged in the path of the sheet beyond said collecting-cylinder, and a continuously-rotating switch comprising a number of switch-fingers rigidly mounted on a shaft to 75 intermesh with said guide-fingers.

80 10. The combination of a pair of cutting-cylinders, a collecting-cylinder, means for leading sheets from the cutting-cylinders to the collecting-cylinder, a continuously-rotating switch rigidly connected to its axle coacting with the collecting-cylinder, means for rendering the switch inoperative, and a folding mechanism arranged in the path of the sheets beyond the collecting-cylinder.

85 11. A delivery mechanism consisting of a set of delivery-tapes, a number of guides, as 38, arranged at an angle to said tapes, so that a wedging-pathway will be formed between the same, a set of tapes running substantially 90 in line with said guides for directing sheets into said wedging-pathway, and a fly mechanism arranged to knock the tail of the sheets down onto the delivery-tapes.

95 12. A delivery mechanism consisting of a set of delivery-tapes, a number of guides, as 38, arranged at an angle to said delivery-tapes so as to form a wedging-pathway, a double set of tapes as a and d , the said tapes a turning back, as over pulley 32, and said tapes d running substantially in line with said guides 38 so as to direct the sheets into said wedging-pathway, and a fly mechanism arranged to knock the tail of the sheets clear of the guide-fingers and tapes d and down onto the delivery-tapes.

100 13. The combination of two pathways, and a continuously-rotating switch.

14. The combination of a long and a short pathway, and a continuously-rotating switch.

In testimony whereof I have hereunto set my hand in the presence of two subscribing witnesses.

ROBERT T. JOHNSTON.
